UNITED STATES PATENT OFFICE.

DEWITT C. CREGIER, OF CHICAGO, ILLINOIS.

IMPROVEMENT IN COMBINED FIRE AND DRINKING HYDRANTS.

Specification forming part of Letters Patent No. 173,768, dated February 22, 1876; application filed September 20, 1875.

To all whom it may concern:

Be it known that I, DEWITT C. CREGIER, of Chicago, in the State of Illinois, have invented a new and useful Combined Fire and Drinking Hydrant; and I do hereby declare the following to be a full and correct description of the same, reference being had to the accompanying drawing, in which—

Figure 1 is a vertical central section of the hydrant. Fig. 2 is a horizontal section on line X X of Fig. 1. Fig. 3 is a horizontal section on line y y of Fig. 1.

The same part is marked by the same letter of reference in the several figures where it occurs.

The nature of my invention consists in the convenient combination in one apparatus of a hydrant for the attachment of hose, a drinking-fountain for men, and a watering-basin for animals, all so arranged as not to interfere with one another, substantially in the manner hereinafter more fully set forth.

In the drawing, A marks the socket for the reception of the branch pipe from the street-main leading to a chamber from which rises the main stem or water-channel of the hydrant, provided with the proper valves and other appliances for regulating the flow of water to the hose-nozzles, the whole forming a fire-hydrant, commonly called a "street-plug." B is a channel cast on the side of the hydrant, and opening below the main operating-valve V.

Its top is suitably formed to receive a cock, D, operated by a slotted crank operated by a rod, E, connected with the handle F pivoted above the spout J at the top of the fountain. The cock D controls the flow of water from the lower chamber of the hydrant to the drinking-nozzle J through a pipe, K, passing up inside an independent channel, N, cast in the water-way of the hydrant. Below the nozzle J is placed a shelf, G, on which a drinking-cup may rest. This shelf is provided with a drip, M, through which the surplus water falls into the basin I, which forms the base of the hydrant, and affords a watering-place for animals. The overflow from this basin is conducted into the gutter or sewer.

As the drinking-water pipe opens at the lower end below the main valve-seat of the hydrant, the water in it is constantly under the head-pressure, and flows freely when the

handle F is depressed and the valve D is opened. When the handle F is released, the weight of the rod E closes the valve D, which is provided with a suitable waste-opening, so that no water can stand in the pipe above D.

In fire-hydrants provided with a supplemental valve, H, this drinking-pipe attachment may be applied or disconnected without shutting off the water in the street-mains. Though when I make a hydrant for the reception of this drinking attachment I prefer to cast the channel B and attach the pipes in the manner hereinbefore described, yet the attachment may be made to existing hydrants, in which no such provision is made, by the use of the ordinary pipe and fittings.

In winter the drinking attachment can be removed, and the opening with which pipe K is connected be plugged up.

It is obvious that the pipe K might, if preferred, be carried down and connected directly with the branch pipe or street-main, and that the channel N might be cast the entire length of the hydrant, and provided with a cock operated in the same manner as D.

These modifications I have contemplated; but I have described and represented the form of hydrant which I have essayed and prefer.

What I claim is—

1. The combination, with a fire-hydrant, provided with one or more hose-nozzles, P, of the pipe K, cock D, rod E, handle F, spout J, shelf G, and basin I, all constructed, arranged, and operating substantially in the manner and for the purposes specified.

2. The combination, in a hydrant, of the channel B, pipe K, provided with a cock, D, operated as described, spout J, and channel N, all arranged and operated as set forth.

3. A fire-hydrant, combined with a drinking-fountain for men and a watering-basin for animals, the hydrant and drinking devices operating independently of each other, and all constructed and arranged substantially as set forth.

The above specification of my said invention signed and witnessed at Chicago this 10th day of September, A. D. 1875.

DEWITT C. CREGIER.
